FIG-3

FIG-2

FIG-1

Arthur Lewyt, Inventor
By his Attorney

Howard D. Hill

UNITED STATES PATENT OFFICE.

ARTHUR LEWYT, OF BROOKLYN, NEW YORK.

BRUSH AND GLASS HOLDER.

1,242,956.

Specification of Letters Patent.

Patented Oct. 16, 1917.

Application filed October 10, 1916. Serial No. 124,852.

To all whom it may concern:

Be it known that I, ARTHUR LEWYT, a citizen of the United States, residing at the borough of Brooklyn, in the county of 5 Kings and State of New York, have invented certain new and useful Improvements in Brush and Glass Holders, of which the following is a specification, reference being had therein to the accompanying drawing.

10 My invention relates to improvements in sanitary tooth-brush and glass holders. More particularly, it has reference to a holder adapted to be hung upon a wall or the back of a sink to retain tooth-brushes in such a 15 manner that they may be covered by a drinking glass, which the holder is also adapted to support. Figure 1 illustrates in perspective a holder embodying an application of my invention. Fig. 2 is a similar view illustrating a modification and showing a drinking glass in position. Fig. 3 is a similar 20 view illustrating another modification, and Fig. 4 is a detail of the brush holder or platform shown in Fig. 1, showing the same 25 in perspective, looking up at the same.

5 indicates a suitable hanger or strap of metal such as brass or steel, provided with a hole such as 6, at the top from which it may be hung from a nail or hook in the wall. 30 This hanger or strap is preferably bent upwardly at the end so as to receive the brush support or platform 7 in the position shown in Fig. 1 or inverted as shown in Fig. 4. This brush support may also be stamped out 35 of sheet metal and may be formed with the socket 8 shown to better advantage in Fig. 4, said socket being adapted to fit over the end 5' of the strap 5. 9 indicates a suitable hole in the support or platform 7 through 40 which the handle of a tooth-brush such as 9' may be introduced as shown.

In the modification shown in Fig. 2 it will be observed that the brush support or platform 7' is formed integrally with the 45 end 5' of the strap 5. In other words, the entire article or holder may be stamped out of a single piece of sheet metal and may be bent as shown in Fig. 2. When in use the

rim of the glass 10 passes between the walls 5-5' of the holder and rests therein as 50 shown.

In the forms shown in Figs. 1 and 3 the platforms 7-7" are preferably provided with a circular groove 11 adapted to receive the rim of the glass 10.

55 From the foregoing it will be seen that my improved holder not only provides support for one or several tooth-brushes, but also provides support for a drinking glass or tumbler, and in such a manner that the 60 tumbler serves as a sanitary shield or guard to protect the brush or brushes from dust or other outside contamination.

Of course it will be understood that various changes may be made in the construction and arrangement of parts without departing from the spirit of the invention as 65 claimed.

I claim:

1. An article of the class described comprising a flat ribbon-like strip of material looped at the bottom and provided with means for hanging the same at the top, and a support in combination with said looped bottom adapted to hold a tooth brush and 75 upon which a glass may be seated, and an annular groove in said support adapted to receive the rim of said glass.

2. An article of the class described comprising a flat ribbon-like strip of material 80 looped at the bottom and provided with means for hanging the same at the top, and a support in combination with said looped bottom adapted to hold a tooth brush and upon which a glass may be seated, and an 85 annular groove in said support adapted to receive the rim of said glass, said support being detachable and adapted for engagement with said loop in an inverted position.

In testimony whereof I hereunto affix my 90 signature in the presence of two witnesses.

ARTHUR LEWYT.

Witnesses:

ETHEL GARDNER,
THOMAS A. HILL.
